Des. 217,700
Patented May 26, 1970

217,700

DESK SET

Ernest J. La Bell, 436 Winnconne Ave.,
Neenah, Wis. 54956

Filed Feb. 24, 1969, Ser. No. 15,886

Term of patent 14 years

Int. Cl. D19—02

U.S. Cl. D74—5

FIG. 1

FIG. 2

FIG. 3

FIG. 4

FIG. 5

FIG. 1 is a generally front perspective view of my new design for a desk set;

FIG. 2 is a front elevational view thereof;

FIG. 3 is a rear elevational view thereof;

FIG. 4 is a side elevational view thereof; and

FIG. 5 is a top plan view of the same;

FIG. 6 is a front elevational view of another embodiment of the desk set shown in FIG. 1 wherein the plaque member is of slightly different configuration and the sides thereof are serrated rather than plain;

FIG. 7 is a rear elevational view of the desk set of FIG. 6;

FIG. 8 is a side elevational view of the desk set of FIG. 6;

FIG. 9 is a top plan view of the desk set of FIG. 6; and

FIG. 10 is an enlarged side edge view of the plaque member of FIGS. 6-9 with portions thereof shown broken away for convenience of illustration.

I claim:

The ornamental design for a desk set, substantially as shown and described.
